UNITED STATES PATENT OFFICE.

FRITZ SCHWARZ, OF MARIENDORF, NEAR BERLIN, GERMANY, ASSIGNOR TO THE FIRM OF DAIMLER-MOTOREN-GESELLSCHAFT, OF UNTERTÜRKHEIM, GERMANY.

GOVERNING DEVICE FOR THE FUEL-ADMISSION VALVES OF COMBUSTION-MOTORS.

1,149,092.

Specification of Letters Patent.

Patented Aug. 3, 1915.

Application filed December 31, 1914. Serial No. 879,965.

To all whom it may concern:

Be it known that I, FRITZ SCHWARZ, subject of the King of Prussia, residing at 28 Friebeinstrasse, Mariendorf, near Berlin, 5 Germany, have invented certain new and useful Improvements in Governing Devices for the Fuel-Admission Valves of Combustion-Motors, of which the following is a specification.

10 My invention relates to combustion motors and more especially to the means for governing the fuel admission of such motors, and it has for its object to provide a governing device adapted to cause the fuel introduced into the cylinder of the motor to be atomized in the most perfect manner.

15 In the governing devices for the fuel admission valves at present in use the lifting of the valve needle pressed upon its seat by a spring is effected in general under governor control by the cam disk, for instance by means of a cam actuating suitable levers or by means of a pawl device lifting the valve lever and releasing it again whenever 20 the valve shall be closed by the valve spring. In all these devices the lifting of the valve needle is effected rather slowly and the fuel is therefore introduced into the cylinder in the form of a continuous jet. It is obvious 25 therefore that a perfect atomizing of the fuel is thereby rendered impossible.

30 According to my invention the valve needle is lifted with a jerk in order to insure a sudden opening of the valve. Immediately after the jerk has acted upon the valve needle and the parts coacting therewith, the needle is again released and the valve is therefore closed instantaneously. By these means the fuel introduced is atomized in an exceedingly exact and perfect 35 manner.

40 A simple means for opening the valve in the manner aforesaid is a lever held in its position of rest by springs and being oscillated, against the action of said springs, by a cam on the cam shaft, said lever after having been released again, being moved by the springs beyond its position of rest and thereby exerting a jerk upon the valve 45 needle or a gear inserted between it and the lever. The spring lever being pushed back by its springs immediately after having actuated the valve needle will at once release the needle and therefore allow the

valve to be closed instantaneously under the 55 action of its spring.

In the drawing annexed to this specification the preferred form of my invention is shown.

a is the fuel valve fixed upon cylinder *b* 60 of the motor.

c is the valve needle pressed against its seat by a spring *d* and preventing the fuel introduced under pressure at *f* from entering the cylinder. A bell-crank lever *g* resting against a washer *c'* on the valve needle is acted upon from time to time by a push-rod *i* connected with a lever *h* rotatably fastened on a fixed axle *h'* and held in its position of rest by two springs *k* fastened 70 to the arms *h''* of said lever. A pawl *m'* on a disk *m* fixed on the cam shaft *n* pushes lever *h* back whenever it passes underneath it and thereby causes springs *k* to act upon the lever in the opposite direction, the lever 75 on being released by the pawl flying in the opposite direction and in passing through and beyond its original position pushing the rod *i* against the bell-crank lever *g*. The jerk so exerted upon the lever causes the 80 valve needle to be lifted quickly and for a moment only from its seat, whereupon it is released and pressed down again upon its seat.

I claim:

1. In a governing device for the fuel admission valves of combustion motors, in combination, a valve, a motor shaft, means adapted to lift the valve off its seat, and means intermittently connected with the 90 motor shaft adapted to impart to said lifting means a sudden jerk in the direction of lifting, the rate of movement of said lifting means being independent of the speed of the motor shaft.

2. In a governing device for the fuel admission valves of combustion motors, in combination, a valve, a motor shaft, a pawl adapted to rotate with said shaft, a spring controlled oscillating lever in the path of 100 said pawl and means connected with said lever adapted to impart a jerk to the valve in the direction of lift.

3. In a governing device for the fuel admission valves of combustion motors, in 105 combination, a valve, a motor shaft, a pawl adapted to rotate with said shaft, a spring controlled oscillating lever in the path of

said pawl, a push rod linked to said lever and a bell-crank lever pivoted to the valve casing, one end of said bell-crank lever resting against a stop on said valve, the other end lying opposite the free end of said push rod.

4. The combination with a spring pressed valve of a combustion motor, of a power shaft, and means actuated by the power shaft for intermittently imparting a sudden blow to the valve in opposition to its spring, for the purpose described, said means being normally disconnected from the power shaft, whereby the rapidity of the valve movement is independent of the speed of rotation of said shaft.

5. The combination with a spring pressed

valve of a combustion motor, of a lever engaging the stem of the valve and arranged to move it in opposition to its spring, a member movable to and from contact with said lever, springs acting on said member in opposite directions and normally maintaining it out of contact with the lever, and means for placing the springs under tension and permitting them to actuate said member to impart a blow to the lever, for the purpose described.

In testimony whereof I affix my signature in presence of two witnesses.

FRITZ SCHWARZ.
